PAUL W. KERR AND ARTHUR E. JONES, OF ELKHART, INDIANA, ASSIGNEES TO HENRY WEIS MANUFACTURING COMPANY, INC., OF ELKHART, INDIANA, A CORPORATION OF INDIANA

HINGE

Application filed November 10, 1930. Serial No. 494,640.

This invention relates to door hinges, and among other objects aims to provide a neat and practicable construction for hinges having the pintle or pivot lying inside the area 5 of the door.

The invention may be readily understood by reference to one illustrative construction embodying the invention and illustrated in the accompanying drawing.

10 In said drawing:

Fig. 1 is an elevation of a swinging door construction.

15 Fig. 2 is a fragmentary horizontal section, on a larger scale, taken on the plane 2—2 of Fig. 1.

Fig. 3 is a fragmentary vertical section taken on the plane 3—3 of Fig. 2.

The invention is here shown embodied in a construction for a swinging door, that is 20 a door which may swing to both sides of the door opening. In doors of this character it is often impracticable or undesirable to place the hinge pintle or pivot either at the edge or outside of the area of the door. The illustrative swinging door 10 is supported on a gravity hinge 11 of an appropriate type which operates by raising the door slightly as it swings to either side of its normal position. The tendency of the door to seek a 30 lower level thus causes it to return to a desired normal position (usually the closed position) after restraint on the door has been released. The attachment of the gravity hinge 11 to the door is such that its pintle 35 or pivot axis lies approximately along the dotted line 12 inside the edge 13 of the door. In many constructions in which gravity and other swinging door hinges are employed it is impracticable to locate the pivot or hinge 40 axis at or outside the edge of the door for reasons which are obvious. In the present case the door is shown recessed at 14 to provide a space for the hinge 11 so that its lower edge may not project substantially beyond the 45 lower edge of the door. While the lower edge of the door 10 is here shown substantially above the floor it is desirable from the standpoint of neatness that the hinge 11 should not project substantially below the lower 50 edge of the door. Where there is a series of

similar doors, this arrangement contributes to a desirable neatness of appearance which is absent in constructions presenting an irregular line along the bottom of the doors.

The pivot axis of the upper hinge 15, which is here represented by the pintle pin 16, coincides with the axis of the lower hinge and therefore lies along the dotted line 12. The pintle 16 is mounted in a generally rectangular frame 17 of channel section which, in the present case, is of the thickness of the door and is positioned between the sheet metal door panels 18 to which it is appropriately secured. The pivot pin may be inserted in its mounting by passing it through openings 19 and 20 in the top of the door and upper leg 21 of the mounting frame 17 respectively and screwing its threaded end 22 into the lower leg 23 of the frame.

The hinge wing is here shown in the form 70 of a double sheet metal strap 24 which embraces and is bolted to opposite sides of the door frame or door jam 25 and extends around the pintle 16. As shown in Fig. 2, its attaching extremities 26 are brought together at 27 beyond which they form a round loop 28 whose internal diameter is substantially that of the pintle 16 which is longitudinally slidable therein. Thus when the door rises and falls in its swinging movements, as indicated by the dotted line 29 (which represents the upper position reached by the door), the pintle 16 slides up and down in the wing loop 28.

Mounted within the opening 30 (which is 80 formed in the door to allow clearance for the edge of the door in swinging beyond the wing 26) is a shield 31 which closes the recess 30 in all positions of the door. The shield is here shown as a hollow cylinder 85 concentric with the pintle 16 and extending flush with the outer edge 13 of the door which is preferably rounded on substantially the same radius as the shield. The shield is made from a sheet metal strip 32 which is 90 bent into cylindrical form leaving a gap 33 at its meeting edges sufficient to receive the doubled shank 34 of the hinge wing. The caps 35 which close the upper and lower ends of the cylinder are provided with central 100

openings 36 through which the pintle 16 passes. The adjoining edges of the cylindrical strip at the gap 33 are held in place and attached to the caps 35 by small drive screws 5 37 which pass through the strip and penetrate the cap on each side of the upper and lower ends of gap 33. The length of the cylinder is made sufficient to accommodate the vertical travel of the door plus the height 10 of the shank 34 of the wings which is here shown reduced (as compared with the attaching extremities 26) in order that the shield or cylinder may be as short as adequate wing strength permits.

15 The connection of the upper hinge may be released merely by unscrewing and withdrawing the pintle 16.

The inner vertical edge 38 of the recess 30 in the door closely adjoins the surface of 20 the cylinder and thus at all positions of the door the cylinder serves to close any gap between the door and the hinge pintle. The outer face of the cylinder may be provided with appropriate plating or any other desired 25 superficial finish to secure a neat and decorative appearance.

It will be noted that the upper hinge construction permits the erection of partitions and swinging doors (such as are found in 30 public toilets and the like) in which the top line 39 of adjoining partitions are flush or level with the upper line of the doors (and therefore leaves no structure to which a hinge above the door line may be attached) as well as eliminating the necessity for a hinge 35 above the door line which is unsightly and breaks the desirable effect of a straight door line.

Obviously the invention is not limited to 40 the details of the illustrative construction since these may be variously modified. Moreover, it is not indispensable that all features of the invention be used conjointly since various features may be used to advantage 45 in different combinations and sub-combinations.

Having described our invention, we claim:

1. A hinge construction of the character 50 described for swinging doors comprising in combination, a pintle holder carrying a pintle adapted to be mounted inside the rear edge of the door, said holder being spaced from said pintle to provide a clear space around said pintle, a hinge member provided with 55 means for connecting the same to the door frame, said hinge member projecting substantially beyond the edge of the supporting means to position it beyond the edge of the door opening and to extend into the area of 60 the door for pivotal connection to said pintle, and a shield surrounding said pintle and said clear space to provide a closure for said space in all positions of the door, said shield having an opening to permit the passage of the hinge 65 member into its interior.

2. A hinge construction of the character described for swinging doors comprising in combination, a pintle holder carrying a pintle adapted to be mounted inside the rear edge of the door, said holder being spaced from said pintle to provide a clear space around said pintle, a hinge member provided with means for connecting the same to the door frame, said hinge member projecting substantially beyond the edge of the supporting means to position it beyond the edge of the door opening and to extend into the area of the door for pivotal connection to said pintle, said pintle and its holder being of substantially greater height than said hinge member to permit said hinge member to slide vertically relative to said pintle, and a shield coaxial with said pintle about which the door is adapted to swing for closing the space about said pintle.

3. A hinge construction of the character described for swinging doors comprising in combination, a pintle holder carrying a pintle adapted to be mounted inside the rear edge of the door, said holder being spaced from said pintle to provide a clear space around said pintle, a hinge member provided with means for connecting the same to the door frame, said hinge member projecting substantially beyond the edge of the supporting means to position it beyond the edge of the door opening and to extend into the area of the door for pivotal connection to said pintle, said pintle and its holder being of substantially greater height than said hinge member to permit said hinge member to slide vertically relative to said pintle, and a cylindrical shield coaxial with said pintle and having a slot therein to permit it to move vertically relative to said hinge member.

4. A hinge construction of the character described, for swinging doors comprising in combination, a pintle holder carrying a pintle adapted to be mounted inside the rear edge of the door, said holder being spaced from said pintle to provide a clear space around said pintle, a hinge member provided with door frame embracing flanges by which the hinge is supported, said hinge member projecting substantially beyond the edge of the supporting means to position it beyond the edge of the door opening and to extend into the area of the door for pivotal connection to said pintle, said hinge member having a narrowed shank and a bore in its extremity through which said pintle passes and being of less height than said pintle so as to be vertically slidably relatively thereto, and a cylindrical shield coaxial with said pintle and having a radius substantially equal to the distance the pintle is inset from the edge of the door, said shield having a vertical slot to receive said narrowed shank and to permit relative vertical movement of said shank in said slot.

5. A swinging door hinge for doors adapted to swing to both sides of the door opening comprising in combination, a hinge pivot adapted to be seated in a recess in the rear 5 edge of the door to space said pivot inwardly of the side edge of said door, a supporting hinge connection operative on said pivot and adapted to be connected with the door support, and a cylindrical housing about said 10 pivot and filling in said recess to maintain the same closed for all positions of said door.
6. A hinge of the character described comprising in combination, a mounting for a hinge pintle including means for attaching the pintle to a door, a hinge pintle carried by said mounting so as to be spaced a distance inside the rear edge of the door, a hinge wing pivotally connected to said pintle and substantially shorter than the pintle to 20 provide vertical sliding movement of said wing on said pintle, and a cylindrical housing concentric with said pintle end of a radius substantially equal to said distance and covering the connection of said wing 25 therewith.
7. A swinging door hinge for doors adapted to swing to both sides of the door opening and having a small vertical travel during their swinging movements comprising in combination a hinge pintle adapted to be seated in a recess in the rear edge of the door so as to be spaced inwardly of said rear edge, a supporting hinge connection longitudinally slidable on said pivot and adapted to be 30 connected with said door support, and a shield associated with said pintle adapted to be seated in said recess to close the latter in all positions of the door.
8. A swinging door hinge of the character 35 described comprising in combination a hinge pintle, a pintle frame open at the sides and the rear edge and carrying said pintle inset from the rear edge of the frame, a hinge member pivoted to said pintle and vertically slidable thereon and having door frame engaging members extending beyond the area 40 of said frame, and a cylindrical shield coaxial with said pintle and filling said frame and having a slot through which said hinge member extends to permit said hinge member to slide vertically relative to said shield, said hinge member and shield being rotatable 45 about said pintle.
9. A swinging door hinge of the character 50 described comprising in combination a hinge pintle having a supporting frame adapted to be set into a recess in the rear edge of the door to place the pintle inside said rear edge, a supporting hinge having means for attachment to a door frame and having a member 55 operable on said pintle, said pintle frame being open at the sides and rear edge to allow clearance for the said hinge member upon the swinging of the door and a cylindrical shield whose radius is substantially 60
- equivalent to the inward spacing of said pintle from the edge of the door, said shield being coaxial with said pintle and adapted to fill the recess in the door to conceal any exposed edge of the recess during the swinging 70 of the door.
10. A swinging door hinge of the character described comprising in combination a hinge pintle having a supporting frame adapted to be set into a recess in the rear edge 75 of the door to place the pintle inside said rear edge, a supporting hinge having means for attachment to a door frame and having a member operable on said pintle, said pintle frame being open at the sides and rear edge 80 to allow clearance for the said hinge member upon the swinging of the door, and a cylindrical shield surrounding and spaced from said pintle to close said recess in the door.
11. A swinging door hinge construction 85 for doors adapted to swing to both sides of the door opening comprising in combination, a hinge structure whose axis is adapted to be located within the area of the door and spaced a distance from the rear edge of the 90 door, said hinge structure including a cylindrical surface coaxial with the hinge axis and having a radius substantially equal to said distance, and a supporting hinge member rotatable about said axis and vertically slid- 95 able relatively thereto and having supporting portions adapted to be connected to the door frame.
12. A swinging door hinge construction 100 for doors adapted to swing to both sides of the door opening comprising in combination, a hinge structure whose axis is adapted to be located within the area of the door and spaced a distance from the rear edge of the door, said hinge structure including a cylin- 105 drical surface coaxial with the hinge axis and having a radius substantially equal to said distance, and a supporting hinge mem- ber rotatable about said axis and having sup- porting portions adapted to be connected to 110 the door frame.
13. A hinge assembly of the character de- 115 scribed, comprising in combination, a pintle mounting open at the sides and rear edge and adapted to be located in a recess in the rear edge of a door, a pintle carried in said mounting and adapted to be spaced inwardly of the rear edge of the door, a hinge member pivoted on said pintle and adapted to be connected to the door frame, and a cylindrical member coaxial with the hinge axis and located in said pintle mounting and adapted to close said recess at all positions of the door.
14. A hinge assembly of the character de- 125 scribed, comprising in combination, a hinge member adapted to have its axis located inside the area of a door within a recess in the rear edge of the door, a second hinge member rotatable about said axis and adapted to be 130

connected to a partition, and a cylindrical member coaxial with the hinge axis and adapted to close said recess at all positions of the door.

5 In witness of the foregoing we affix our signatures.
